TOOL SHIELD

Elmer F. Pfaff, Mantua, and Robert W. Henning, Rocky River, Ohio, assignors, by mesne assignments, to Olin Mathieson Chemical Corporation, a corporation of Virginia

Application November 12, 1954, Serial No. 468,358

5 Claims. (Cl. 1—44.5)

This invention relates to a fastener driver and more particularly to an explosive operated stud driving tool.

In the use of explosive operated tools of the type disclosed in U.S. Patent Nos. 1,365,869 and 1,365,870 for driving studs or pins into structural materials it is often desirable to install the studs into rounded cylindrical objects such as columns, rods, poles, and pipe, for example. In such installations it is not only difficult to properly position the tool for projecting the fastener, but the operation of driving studs into these round structures creates an extremely hazardous situation. It will be appreciated that in installations of this type as compared to installations where stud driving occurs squarely into substantially planar surfaces, there is a greater tendency for the fastener to ricochet and endanger those in the vicinity of the operator and that ricochetting of such off-angle fasteners is of greater concern than the "flash" and occasional "flash" swept particles which may accompany the driving operation. Heretofore available types of tools, including those with shields, pads or guards, have provided no improvement in this respect over the tool with an unguarded muzzle.

Therefore, one object of the invention is to provide an improvement in explosive operated fastener driving tools for enabling the setting of fasteners properly into cylindrical or other curvilinear surfaces of like nature.

Another object is the provision of a new self-aligning tool assuring on round surfaces controlled and safe operation of explosive actuated driving tools in all directions on such work surfaces.

Another object is the provision of a new and improved tool with a muzzle structure which substantially eliminates the likelihood of a fastener escaping into free flight as a result of inability of center the tool with round work surfaces properly.

A still further object is to provide on such tools a self-centering and aligning safety shield for receiving spall particles and the blast from the muzzle thereby protecting not only the tool operator but also protecting other workmen in the vicinity from ricochetting missiles.

Other objects and advantages will be evident from the description and the accompanying drawing of preferred embodiments of the invention in which:

Figure 1 is an elevational view partly in cross-section showing part of a driving tool in accordance with one embodiment of this invention;

Figure 2 is a fragmentary perspective view showing the muzzle end of the tool positioned against the work ready for driving operation;

Figure 3 is an elevational view partly in cross-section showing a second embodiment of the tool of the present invention; and

Figure 4 is a plan view of the embodiment of Figure 3 taken on line IV—IV of Figure 3.

In accordance with this invention the muzzle end of an explosive actuated stud driving tool is provided with a safety shield adapted to center itself on the surface of cylindrical parts and to substantially retain disrupted par-

2

ticles such as spall fragments and the like within the shield structure. The shield or muzzle guard pad of this invention comprises a box-like structure opened at one side at which it is presented to the work and having peripheral notches which enable the shield and the tool associated with it to be aligned properly with the work surface. Specifically, the side walls of the shield are notched in accordance with this invention. A V-notch at any suitable angle in each of a pair of opposing walls is contemplated which will accommodate the rounded surfaces usually encountered. The shield or muzzle guard may be provided with a notch having a fixed angle or a variable angle. When cylindrical objects of relatively large diameter constitute the work, the angle of the notch is preferably near but somewhat less than 180°. When cylindrical object of small diameter constitute the work the notch is at a more acute angle. Although for a given angle of notch a considerable range of work diameters can be handled, the range can be extended by providing a shield in accordance with this invention having an adjustable V-notch. Furthermore, in accordance with a preferred form of the invention, it is contemplated that the open side of the shield structure adjacent the notches be provided with enclosures in the form of plates or the like the better to retain disrupted and ricochetting materials.

The embodiment of Figures 1 and 2 is illustrated in connection with the muzzle portion of a tool of the type disclosed in the copending application of Kopf, Henning and Marsh, Serial No. 355,034, filed May 14, 1953 for explosively actuated tools. A tool of this type comprises an outer barrel tube or housing 1, mounted for movement on barrel 2 so that the housing may be pushed forward relative to the barrel 2 into operative relationship when the tool barrel muzzle is placed against the surface into which the stud is to be installed and the tool pressed firmly against such surface. This type of tool also includes a shield tube or sleeve 3 for mounting the shield and a barrel spring 4, which is a compression type of spring adapted to press against the inner flange 5 of shield tube 3 so as to urge the tube and shield forwardly. The barrel is threaded at the muzzle 10 and carries a thread cap 9 which serves to transmit the thrust of barrel spring 4 acting through sleeve 3 to the barrel 2 and also as an axial retainer for the shield or muzzle guard structure.

In this embodiment as shown in Figures 1 and 2, the self-centering safety shield structure takes the form of a receptacle consisting in general of a rear safety plate 6, which is apertured at 20 to receive the tool barrel 2, the four side walls 11, 12, 13 and 14, two of which are notched, and the partial closure plates 17 and 18 at the extremities of the notches, disposed at an angle and spaced, leaving the area between the apex of the notches open. At the aperture 20 the safety shield is adapted to be attached at the muzzle of the barrel tool coaxially in any suitable manner as by being fixed on shield tube 3 which is constrained axially to have limited movement between cap 9 and spring 4. Although the invention described in connection with this embodiment is adapted to be attached to this form of explosive driving tool, it is to be understood that the invention in its general concept is not limited to the structural details or the arrangement of parts of a tool since the invention is adapted to be used with various forms of explosive operated tools or the like.

The apertured safety plate 6 shown has a rectangular form provided at the marginal or peripheral portions with side walls which in turn are provided with partial front enclosures all of which with the plate define a hollow guard and alignment structure. Two of these side walls, 11 and 12, are V-notched to match at an angle the apex

of which is designated in Figure 1 as 8. It is to be noted that the inner dihedral angle at apex 8 is advantageously somewhat more acute than the outer angle defined by the end guard plates 17 and 18. The interior portion of the box-like shield structure of this embodiment is lined with a shield pad 7 of resilient material such as a heat resistant synthetic rubber which may be molded into the steel housing of the shield to extend over the plate 6 and also over portions of the side walls 11, 12, 13 and 14. On the exterior the shield structure may be provided with pairs of guide lines or indicia marks 15 and 16 as shown in Figure 2 for the purpose of enabling the tool operator to readily and more accurately position the tool at a desired location for insertion of a fastener. Although in this embodiment the safety shield plate 6 and the self-aligning shield structure is shown to have a rectangular form, other forms such as a circular form may also be employed.

The plate 6 and side walls 11, 12, 13 and 14 may be advantageously formed integrally from a single sheet of metal such as steel of suitable thickness to prevent penetration by deflected fragments. In this event, the rear plate 6, which prevents rearward projection of flash and fragments, is provided with marginal extensions making notched side walls 11 and 12 and unnotched side walls 13 and 14 all four of which together provide a protective flange portion to substantially prevent excessive lateral deflection of flash and particles trained in the flash. Forward ejection of missiles is substantially prevented by the spaced angle plates defining the outer portion or extremities of the dihedral angle formed by the notches. The rear plate 6 and the side walls form an enclosure about the muzzle of the tool together with the angle plates, except for the apertured portion 20 adapted to permit passage of the muzzle of the tool barrel and except for the opening at apex 8.

The notched side walls 11 and 12 are oppositely disposed about rear plate 6 and carry V-shaped cut-outs disposed with suitable accuracy in side walls 11 and 12 in relationship with rear plate 6 and the tool barrel aperture 20 therein so as to place the axis of the tool barrel perpendicular to the portion of the cylindrical surface into which the fastener is to be projected. Thus side walls 11 and 12 are of generally identical geometrical construction as far as the shape and the location of the V-notch in each is concerned. While it is preferred that the aligning cut-out portion of the shield structure of this invention takes the form of an angular V-notch, it will be appreciated that other forms may be employed of any special shape complimentary or adaptable to special surface shapes encountered in work surfaces into which an explosively driven fastener is to be emplaced. In the embodiment shown in Figures 1 and 2 the notch is angular and embraces an included angle of about 120° at the apex 8 and an included angle of about 150° at the extremities adjacent plates 17 and 18. The difference in the inner and outer angle enables the muzzle fixture of this invention to accommodate a wide range of radii of curvature encountered on the rounded surfaces.

In operation the tool, loaded with a fastener and an explosive charge, is placed into position for firing with the self-aligning shield structure of this invention in engagement with the cylindrical surface of a piece of work which is to provide support or which is to be supported with the aid of a fastener driven into the surface. As illustrated in Figure 2 part of the marginal portions of the side walls 11 and 12 are pressed against a piece of work taking the form of a circular cylindrical tube 19 which may be a pipe or column only a part of which is shown. After the explosive operated tool is positioned by the operator at a desired point on the work 19 with the aid of locating marks 15 and 16, which may take the form of indentations (Figure 1) or of superficially applied indicia marks, the operator then pushes the tool against the cylindrical surface of object 19 until parts of the marginal portions of notched sides 11 and 12 at

either apex 8 or at the plates 17 and 18 are firmly in engagement with the cylindrical surface. This places the entire shield structure in proper alignment and centered position on the cylindrical surface of the work 19. 5 Because of the structural relationship of the notched side walls 11 and 12, and the apertured rear plate 6, it will be evident to those skilled in the art that the barrel of the tool is positioned squarely to the tangential plane at the point of the surface of object 19 into which it is 10 desired to drive a stud. In this position it will be noted that the shield structure of this invention engages a surface of the pipe, or column into which the stud is to be driven so as to not only protect the tool operator from any flying particles at the time of firing but also to position the tool at a desirable firing angle at which danger of a glancing shot is substantially eliminated. With the tool thus positioned and fully compressed against the target surface, it may be fired in safety.

In the embodiment of Figures 3 and 4 there is shown 20 a form of the device of this invention having an adjustable notch angle which permits a single shield structure to be used in connection with a maximum range of diameters of cylindrical surfaces including sharply curved surfaces as well as gently curved surfaces. As in the 25 previous embodiment there is a rear safety plate 6 carried on the front end of tube 3 and having an internal flange 55 about an aperture 20 for passage of the barrel 2 of an explosive operated stud driving tool. At the muzzle of the barrel 2, there is mounted any suitable 30 form of retainer cap 99 functioning much like cap 9 of the previous embodiment. The side walls, however, are in this embodiment formed by a pair of movable yoke-shaped opposing sectors 21 and 22 including arcuate side walls and lateral sections made of metal such as 35 steel and adapted to be carried at the ends of their lateral sections pivotally by the plate 6 at the headed pins 23 and 24 fastened in any suitable manner as by means of threads in bosses 46 and 47 of plate 6. The inside of the shield structure is provided as in the preceding 40 embodiment with a resilient heat-resistant lining 25 which is preferably of a somewhat heavier section attached to the rear plate 6 and slidably bearing against the interior surface of the sectors 21 and 22. Sectors 21 and 22 are provided with partial front cover plates 48 and 49 respectively.

The shield is further provided with additional elements for securing movement of the sectors in unison in order that the axis of the barrel will always lie in the plane of bi-section of the dihedral angle formed by the anterior 50 marginal edges of sectors 21 and 22. For this purpose plate 6 is provided with a pair of slotted extensions 26 and 27, sector 21 is provided with a pair of perforations or apertures 28 and 29 and in like manner sector 22 is provided with a pair of perforations 30 and 31. Extending between each of the apertures in sectors 21 and 55 22 and one or the other of the slots 40 and 41 in the extensions 26 and 27 respectively is one of the four links 32, 33, 34 and 35. One end of each link is pivotally connected at a perforation while the other end of the link is both pivotally and slidably mounted with respect to one or the other elongated slot of extensions 26 and 27 by means of a suitable pin and manually releasable fastener arrangement hereinafter described.

The embodiment of Figures 3 and 4 may be described 60 in greater detail as to its component parts.

Sector 21, which is adapted for arcuate movement, includes lateral sections 36 and 37 and front cover plate 48; and likewise sector 22 includes lateral sections 38 and 39 and front cover plate 49. Each of the lateral sections is pierced at the convergent ends for pivotal connections 70 with one or the other of the pins 23 and 24 by means of which sectors 21 and 22 are pivotally mounted on plate 6 in articulated relationship. The anterior edges of lateral sections 36 and 38 of sectors 21 and 22 respectively are adapted to form one of the variable V-notches 75

while lateral sections 37 and 39 of sectors 21 and 22 respectively are adapted to form the other opposed V-notch. The space between sections 36 and 37 is partially enclosed by plate 48 and in like manner plate 49 partially encloses the space between sections 38 and 39.

Lateral sector 36 is provided with a perforation 28 at which pivotal connection is made with link 32 at the other end of which pivotal connection is made slidably with a slot 40 in extension 26 by means of pivot screw 44. Lateral sector 38 is formed with perforation 30 at which pivotal connection is made with link 34 which in turn is connected pivotally in slidable relationship with slot 40 of the extension 26 also by means of screw 44. In like manner at perforations 29 and 31 lateral sections 37 and 39 respectively are pivotally connected with links 33 and 35 respectively which links in turn are pivotally connected slidably in slot 41 of the extension 27 by means of screw 45. Extensions 26 and 27 with the elongated slots 40 and 41 respectively are disposed on plate 6 in perpendicular relationship with the plate 6, adjacent the lateral sectors 36, 37, 38 and 39 so that the slots 40 and 41 extend in parallel relationship to the axis of the tool barrel and the shield tube or sleeve 3 the latter of which is mounted coaxially with the tool barrel. This arrangement of parts permits the sectors 21 and 22 to move arcuately in desired unison which movement presents the axis of the tool barrel always squarely to the work surface at any of the angles of the V-notch obtainable with this embodiment. Sectors 21 and 22 can be fixed at the will of the tool operator at any setting of the V-notched angle desired by means of a T-head pivot screw and knurled or wing nut arrangement such as pivot screw 44 and knurled head clamp nut 42 in slot 40 for connection with links 32 and 34 and such as pivot screw 45 and knurled head clamp nut 43 passing through slot 41 for connection with links 33 and 35. It is evident that the pivot screws 44 and 45 may be modified to serve merely to pivotally carry the end of the links in slidable relationship with respect to the slots 40 and 41 and that the pivot pins 23 and 24 instead may be provided with a clamping arrangement to hold the desired angular setting of the notches.

In this embodiment the resilient liner 25 may advantageously take the form shown in Figure 3 which includes forwardly extending side wall sections extending from the section of the pad 25 attached to plate 6 only partially to the edge section of and along the interior of sectors 21 and 22. This skirt portion of resilient pad 25 acts as a seal between sectors 21 and 22 and the plate 6, thereby minimizing flash which would be a source of considerable discomfort to the tool operator.

In operation of the embodiment of Figures 3 and 4, the clamping nuts 42 and 43 are first loosened to permit adjustment of the V-notch angle to a desired value suitable to an object such as 50 after which the nuts are tightened to hold this angle as in the preceding embodiment. Thereafter, as in the previous embodiments, it is merely necessary to press the shield structure of this invention and the loaded explosive operated tool associated therewith against the curvilinear surface of object 50 into which explosive driven studs are to be forceably emplaced. This action, as in the previous embodiments, allows the housing 1 to move forwardly with respect to the shield structure and barrel to further compress barrel spring 4 while the cap 99, attached with screw threaded adjustability on the muzzle of barrel 2, is positioned to abut with the surface of the object as in the previous embodiments described in connection with the tool of the aforementioned Serial No. 355,034.

Since many other embodiments of this invention may occur to those skilled in the art, it is to be understood the foregoing is intended by way of illustration of an embodiment now believed to be preferred and not as a limitation of the scope of the present invention except as set forth in the appended claims. For example, it will be

understood that the rear plate 6 of the shield may itself be folded to provide the dihedral angle which constitutes the V-notch set forth hereinbefore.

What we claim is:

- 5 1. A self-aligning shield structure for an explosively actuated stud driving tool comprising a plate apertured for passage of a tool barrel squarely therethrough and provided at the marginal portion thereof with forwardly extending side walls forming a gas expansion and missile 10 confining chamber, said side walls having an edge profile including a pair of oppositely disposed V-notches adapted to position the plate in parallel with and said barrel perpendicular to the tangential plane passing through a point on a cylindrical surface at which a stud is to be driven into the surface by said tool, said side walls having a pair of partial front protective cover plates disposed remotely from and about the opening between the apexes of the V-notches.
- 20 2. A self-aligning shield structure for an explosively actuated stud driving tool comprising a rectangular rear plate apertured for passage of a tool barrel squarely therethrough and provided at the marginal portion thereof with forwardly extending side walls forming a gas expansion and missile 15 confining chamber open at the front, said side walls including an oppositely disposed pair of notches at substantially identical included angles whereby the axis of the barrel of said tool is presented substantially squarely to the surface at the point at which a stud is to be explosively driven, wherein each of said 25 notches consists of a relatively acute angle at the apex and a less acute angle at the extremities of the notched walls.
- 30 3. A self-aligning shield structure for an explosively actuated stud driving tool comprising a rectangular rear plate apertured for passage of a tool barrel squarely therethrough and provided at the marginal portion thereof with forwardly extending side walls said side walls being provided at the forward edge with a pair of spaced 35 front cover plates, said rear plate, side walls and cover 40 plates forming a gas expansion and missile confining chamber open at the front, said side walls including an oppositely disposed pair of walls spanned by said cover plates and notched at substantially identical included angles whereby the axis of the barrel of said tool is presented substantially squarely to the surface at the point at which a stud is to be explosively driven.
- 45 4. A self-aligning shield structure for an explosively actuated stud driving tool comprising a plate apertured for passage of a tool barrel squarely therethrough and provided at the marginal portion thereof with forwardly extending side walls forming a gas expansion and missile 50 confining chamber, said side walls having an edge profile including a pair of oppositely disposed V-notches adapted to position the plate in parallel with and said barrel perpendicular to the tangential plane passing through a point on a cylindrical surface at which a stud is to be driven into the surface by said tool, said notches each consisting of a relatively acute angle at the apex and a less acute angle remotely from said apex at the 55 extremities of the notched walls, said side walls having a pair of partial front protective cover plates disposed remotely from and about the opening between the apexes of the V-notches.
- 60 5. In a tool for explosively driving studs into cylindrical surfaces, a barrel through which the stud is ejected and a self-aligning shield structure mounted about the muzzle end of said barrel to extend outwardly around the barrel for engagement with the surface into which the stud is to be inserted, said shield comprising anterior 65 portions forming a dihedral angle the bi-section of which includes the axis of said tool barrel, said portions being adapted to be presented in abutment with a cylindrical work surface whereby the barrel of the tool may be readily aligned in centered squared relationship to said surface, and wherein said shield on readily visible por-

2,925,600

7

tions of the exterior has thereon indicia marks adapting the tool to positioning with respect to each particular spot on the cylindrical surface at which it is desired to drive a stud.
